COSTUMER

James V. Vevirit, Kenmore, and Francis J. Ihlenfeld,
Cheektowaga, N.Y., assignors to McDonald Products
Corporation, Buffalo, N.Y.

Filed Apr. 29, 1964, Ser. No. 79,735

Term of patent 14 years

(Cl. D33—8)

FIG. 1 is a perspective view of a costumer, showing our new design for a floor to ceiling pole unit;

FIG. 2 is a top plan view thereof;

FIG. 3 is a bottom plan view thereof;

FIG. 4 is a perspective view of the dominant features thereof, on an enlarged scale, the hooks being shown in open position; and

FIG. 5 is a corresponding view thereof with the hooks in closed position.

The sides not shown are identical to the sides which are shown.

The characteristic feature of our design resides in the combination on a costumer pole of the swivel mounted hook members which penetrate the pole in a crossed relationship in open position and nest within slots when closed, as particularly shown in FIGS. 4 and 5.

We claim:

The ornamental design for a costumer, substantially as shown and described.
